(57) **CLAIM**

The ornamental design for a chair back, as shown and described.

DESCRIPTION

FIG. 1 is a front perspective view of a design for a chair back;
FIG. 2 is a front elevational view of the design shown in FIG.
1;

FIG. 3 is a bottom elevational view of the design shown in
FIG. 1;

FIG. 4 is a side elevational view of the design shown in FIG.
1 in which the opposite side is a mirror image;

FIG. 5 is a top elevational view of the design shown in FIG. 1;
and,

FIG. 6 is a perspective view of a chair incorporating the chair
back of the present design in which the chair components
shown in broken lines are environmental structure for illus-
trative purposes only and form no part of the claimed design.
